UNITED STATES PATENT OFFICE.

CHARLES S. PECK, OF DANBURY, CONNECTICUT.

MACHINE FOR DIPPING HATS.

SPECIFICATION forming part of Letters Patent No. 540,802, dated June 11, 1895.

Application filed October 8, 1894. Serial No. 525,238. (No model.)

To all whom it may concern:

Be it known that I, CHARLES S. PECK, a citizen of the United States, residing at Danbury, in the county of Fairfield and State of Connecticut, have invented certain new and useful Improvements in Machines for Dipping Hats; and I do hereby declare the following to be a full, clear, and exact description of the invention, such as will enable others skilled in the art to which it appertains to make and use the same.

My invention has for its object to produce a machine for dipping hat bodies upon the cone, every movement of which shall be automatic, which will lower the body into the tank and will also raise it therefrom with a retarded movement, that is to say, when the body is descending or sinking in the tank the movement will be fastest at the start and will grow slower to the end of the movement so that there shall be no danger whatever of forcing air within the body through it violently so as to rupture or injure the body, and the movement of the body in rising will also be fastest at the start and will grow slower to the end of the movement, the effect being to compact the fur in the body together sufficiently to permit it to be readily removed from the cone, and also to prevent splashing of water from the tank, as necessarily results if the last portion of the upward movement of the cone and body is made too rapidly, thus making the operation of the machine fastest when no injury can result from rapid movement and relatively slow at the times when it is possible for injury to the bodies to result from rapid movement, and for the water in the tank to be splashed out, which is a serious inconvenience in use.

My invention has for its object furthermore to provide an adjustment which will determine the length of time which the body shall remain submerged, it being of course understood that certain grades of bodies in order to get the best results require to remain submerged much longer than other grades of bodies do. The operation of my novel machine is such that if it is desired to have the body begin to rise the instant that the sub-

merged so as to permit the body to remain submerged for any required length of time before the upward movement commences.

My invention furthermore relates to various novel mechanisms and arrangements and combinations of elements for producing the desired results which will hereinafter be fully described and then specifically pointed out in the claims.

In the accompanying drawings, forming part of this specification, Figure 1 is a side elevation of the machine complete; Fig. 2, a section on the line *x* *x* in Fig. 1, looking toward the left; Fig. 3, a section on an enlarged scale on the line *v* *v* in Fig. 4, looking toward the left; Fig. 4, a section on the line *w* *w*, indicated in Figs. 1 and 5, looking up in Fig. 1 and toward the left in Fig. 5; Fig. 5, a section of the main shaft on the line *o* *o* in Fig. 4, looking toward the right, the parts being shown out of their actual position, but corresponding to the position in which they appear in Fig. 4, the engaging-lug appearing in full lines at the top of its normal position relative to the other parts and in dotted lines at the bottom in the position it occupies at the instant the hat-body is wholly submerged in the tank and the lowering mechanism is stopped; Fig. 6, a section of the main shaft, likewise on the line *o* *o* in Fig. 4, but showing the parts at their normal position—that is, a position in which the machine is ready to be started to lower a hat-body; Fig. 7, a similar view, the engaging-lug having moved to the position it occupies when in engagement with the crown-teeth on the large gear-wheel; Fig. 8, a section on the line *p* *p* in Fig. 1, the main shaft and locking-cam being in end elevation, as seen from the left in said figure; Fig. 9, a section on the line *y* *y* in Fig. 1, looking toward the right; Fig. 10, a similar view on the line *z* *z* in Fig. 1, said views showing, respectively, the positions of the eccentrically-pivoted elliptical raising and lowering gears at the instant the lowering operation commences; Fig. 11, a detail end elevation on an enlarged scale, the point of view being from the right in Fig. 1 and the sprocket-wheel being removed; and Fig. 12 is a section on the line *s* *s* in Fig. 11, the sprocket-wheel being in place. It should be noted that Figs.

3 to 12, inclusive, are all on the same scale, which is an enlargement of the scale in Figs. 1 and 2.

1 denotes framework which may be of any suitable design and is ordinarily adapted for attachment to the ceiling or to overhead beams. It may however, be supported by standards if preferred.

Power is applied to drive the machine by a belt 2 running over a cone pulley 3 and passing through a belt shifter 4 of ordinary construction. The shifting lever 5 is provided with a latch 6 which is adapted to engage notches in a plate 7 to lock the belt shifter, and with it the belt in any required position on the cone pulley. By the use of a cone pulley and belt shifter I am enabled to increase or decrease the speed of the machine at any time by a slight movement of the lever in either direction as may be required.

Belt pulley 3 is carried by a shaft 8 which is the driving shaft of the machine. This shaft is suitably journaled on the frame and carries in addition to the cone pulley a pinion 9 and a spiral gear 10.

11 denotes the main shaft which is suitably journaled on the frame above the driving shaft.

At the right end of the machine as seen in Fig. 1 and below the main shaft is a shaft 12 which I term the secondary shaft.

At the right end of the main shaft as seen in Fig. 1 is journaled the dipping wheel 13, in the present instance a sprocket wheel, over which a sprocket chain 14 passes, one end of said chain being secured to the wheel as indicated in Fig. 1. A rope or cord may of course be substituted if preferred. At the other end of the sprocket chain is attached the usual carrier 15 upon which the cones with hat bodies thereon are placed for submersion in the tank, which is denoted by 16.

17 denotes a large gear wheel having a hub 18 which turns freely on the main shaft. This gear wheel meshes with pinion 9 and is always turning when the machine is in use.

The inner face of gear wheel 17 is provided with crown teeth 19 which are adapted to be engaged by a lug 20 on a sliding block 21 carried by a plate 22 which is rigidly secured to the main shaft. I have shown this block as moving on ways at the sides of a recess 23 in the plate and as moved forward by a spring 24 socketed in plate 22 below the block. See Fig. 7. Upon the outer face of the block is a rigid latch 25 which is adapted to engage a lever 26 pivoted to an arm 27 depending from a block 28 which is rigidly secured to or cast integral with a bracket 29 the latter being rigidly bolted to the frame as clearly shown in Fig. 1. The shape of this lever is clearly shown in Figs. 5, 6 and 7, which see in connection with Fig. 1. The special outline of the lever is of course not of the essence of my invention, the essential requirements being a surface 30 for engagement by latch 25, a notch 31 adapted to engage a pin 32 projecting out-

ward from the block, and a notch 33 and a surface 34 both of which are adapted to be engaged by a stump 35 which lies in a slot 36 in block 28, said stump projecting outward from a block 37 which is adapted to slide in a recess in block 28, said block 37 being normally held at the raised position by a spring 38 socketed in block 28 below block 37.

39 denotes a rod connected to block 37 and passing down within spring 38 and through block 28, to the lower end of which an operating cord 40 is attached. See Figs. 1 and 2.

41 is a cross pin in rod 39 which engages the under side of block 28 and limits the upward movement of the rod.

As already stated the large gear wheel is always moving when the machine is in use. When it is desired to dip a hat body the operator simply pulls down upon operating cord 40 and from this instant the operation of the machine in lowering the hat into the tank, holding it submerged for the length of time that has been determined upon and raising it again out of the tank is automatic.

The normal position of the parts just described is shown in Fig. 6.

When the operator pulls down upon the operating cord he moves block 37 down to the position shown in Fig. 7. This permits spring 24 to move sliding block 21 which carries the engaging lug outward and moves lever 26 to the position in which it is shown, that is to say, stump 35 will have moved downward far enough so that the bearing surface which normally rests against the stump will pass forward over the stump and the stump itself will lie in notch 33. This movement of sliding block 21 carries the engaging lug outward far enough to place it in engagement with crown teeth 19 on the large gear wheel. The actual engaged position of the lug with the crown teeth is not shown in the drawings but will be readily understood from Figs. 1 and 2, more especially Fig. 1, in which the engaging lug is shown as registering with a space between two crown teeth from which position it would simply move forward toward the point of view to be in engagement with the teeth.

The instant the lug becomes engaged with the crown teeth motion is imparted to plate 22 and a half revolution is imparted to the main shaft which lowers the body into the tank as will presently be more fully explained. At the instant the body is at the lowered position in the tank the engaging lug and sliding block 21 will be at the position shown in dotted lines at the bottom in Fig. 5, that is to say, latch 25 will have engaged a cam 42 on a sliding collar 43 on a rod 44, the respective ends of which are rigidly secured to the frame as indicated in Fig. 1, the downward movement of collar 43 on the rod being limited by a pin 55. The effect of the engagement of latch 25 with cam 42 will be to force the latch and with it the sliding block and engaging lug backward as clearly indicated in dotted lines in Fig. 5 and will move said lug out of

engagement with the crown teeth on the large gear wheel thus instantly stopping the rotation of the main shaft, in which position all of the parts will remain, the hat body being wholly submerged in the tank, until lug 20 is again placed in engagement with the crown teeth as I shall presently explain. In order to insure that the main shaft will be locked in position instantly when it has completed each half revolution I provide a plate 45 at the end of the main shaft, see Fig. 8 and at the left in Fig. 1, which is provided on opposite sides with notches 46 adapted to be engaged by a roller 47 carried by an arm 48 the lower end of which is in the present instance pivoted on the driving shaft. See Fig. 1. The roller is held in engagement with the periphery of the cam and is forced into the notches by a spring 49 carried by a threaded rod 50 which is adjustable in a bracket 51 itself rigidly secured to the arm. See Figs. 1 and 8. The tension of the spring and consequently the pressure of the roller upon the cam are adjusted by turning the rod in or out as may be required and locking it in position after adjustment by a check nut 52.

53 denotes a rod the respective ends of which are rigidly secured to the frame and 54 a block adapted to slide thereon, the downward movement of the block upon the rod being limited by a collar 56.

57 denotes a screw shaft the ends of which are journaled in hubs 58 themselves rigidly secured to the frame. 59 is a collar on the screw shaft which bears against the upper hub to prevent upward movement of the shaft and 60 is a spiral gear on said shaft which rests upon the lower hub and meshes with spiral gear 10 on the driving shaft, see Fig. 2, so that the screw is kept continually in rotation when the machine is in use.

At the outer end of block 54 is a recess 61 through which the screw passes but without contact therewith. Pivoted in this recess is a lever 62 which carries a block 63 the face of which is threaded to correspond with the thread of the screw shaft. A spring 64 acts to hold the threaded block normally out of engagement with the thread of the shaft as in Figs. 2 and 3. In the drawings I have shown the spring as connected to the lower end of the lever and as provided with a curved plate 65 which bears against the screw shaft below the threaded portion as is clearly shown in Fig. 2.

66, see Figs. 2 and 3, denotes a cam on a collar 67 rigidly secured to the main shaft. The operative position of this cam is indicated in dotted lines in Fig. 3 and its operation will be clearly understood from this figure. When latch 25 is in the position shown in Fig. 6 the cam is in the position shown in full lines in Fig. 3. When the cam has completed a half revolution and is in the position indicated by dotted lines at the bottom in Fig. 5 the cam will be in the position shown in dotted lines

in Fig 3 and will force the lever inward and will place the threaded block in engagement with the thread of the screw shaft in which position the parts will remain, owing to the stopping of the rotation of the main shaft as already described until the main shaft starts again and the cam passes out of engagement with the lever, the screw shaft however, being continuously in rotation. It is obvious that when the threaded block is in engagement with the screw shaft the rotation of said shaft, in the direction indicated by the arrow in Fig. 3, will raise block 54 on rod 53 by 80 which it is carried.

68 denotes a lug projecting outward from block 54 and which is engaged by a rod 69, a portion of which is threaded. This rod is provided at its upper end with a collar 70, to prevent it from being wholly withdrawn from the lug, at its lower end with a hand wheel 71 for convenience in operation and between the collar and hand wheel with collars 72 both of which are rigidly secured to the rod and which retain between them a collar 73, not secured to the rod, which carries an arm 74 the outer end of which is bifurcated, the branches being curved to partially inclose rod 44. It is of course obvious that rotation of rod 69 will raise or lower said rod through the engagement of the thread thereon with lug 68 and will consequently raise collars 72 and 73 and arm 74 relatively to block 54.

The operation of this portion of the machine is as follows: When the rotation of the main shaft causes cam 66 to engage lever 62 and place the threaded block in engagement with the screw shaft, block 54 and with it rod 69 and arm 74 will be raised until the branches of said arm, which partially inclose rod 44, will come in engagement with sliding collar 43 on said rod and will raise cam 42 on said collar out of engagement with latch 25. See Figs. 4 and 5. This will permit lug 20 on sliding block 21 to again engage crown teeth 19 on the large gear wheel which instantly communicate motion to the main shaft. The instant the main shaft commences to move again cam 66 on said shaft will pass out of engagement with lever 62 and spring 64 will at once move the threaded block out of engagement with the screw shaft. This of course releases block 54 and permits it to drop down on rod 53 until it is stopped by collar 56.

In order to prevent positive engagement of cam 66 with lever 62, which may lead to breakage of parts should the thread upon the block fail to engage the thread of the screw shaft, I provide a strong spring 75 on the back of lever 62 which is engaged by the cam. This spring is strong enough to overcome the power of spring 64 and hold the threaded block in engagement with the thread of the screw shaft but will yield should the threads of the block not register for any reason with the thread of the screw shaft at the instant of engagement. It will of course be apparent that should the threads fail to engage at the instant of con-

tact they will engage an instant later owing to the rotation of the screw shaft and the yielding of spring 75.

It will be understood from the description already given that until cam 42 on sliding collar 43 is raised sufficiently to permit latch 25 to resume its normal position and lug 20 to engage the crown teeth on the large gear wheel the hat body which has been lowered into the tank will remain submerged. The length of time that the body remains submerged will depend of course on the adjustment of arm 74 which is carried by rod 69, it being apparent that if said arm is raised high enough so that it will engage sliding collar 43 an instant after latch 25 is moved back by cam 42 and the engaging cam thrown out of engagement with the crown teeth, the upward movement of the hat body will commence immediately, and that just as long a period of submersion as may be required can be obtained by rotating rod 69 and moving arm 74 downward, it being of course understood that collars 72 rotate with the rod so that the rod turns freely in collar 73 which carries the arm.

The rotation of the main shaft and consequently the rasing of the hat body from the tank will continue until the second half revolution of the main shaft is completed and latch 25 has engaged lever 26 and been moved backward thereby carrying the engaging lug out of engagement with the crown teeth, this position being clearly shown in Fig. 6 which see in connection with Fig. 1. It will be noticed in Figs. 6 and 7 that notch 33 in lever 26 and stump 35 are both slightly rounded so that the instant latch 25 has passed off from lever 26, that is, the instant the parts move out of the position shown in Fig. 7, spring 38 will raise block 37 and stump 35 will pass out of notch 33 and will move the lever back from the position shown in Fig. 7 to that shown in Fig. 6 the backward movement of the lever being stopped by pin 32, as clearly shown in Fig. 6, the parts remaining in this position until the dipping mechanism is started again by another pull upon the operating cord. As the second half revolution of the main shaft is completed latch 25 will pass on to lever 26 and will be forced inward thereby moving the engaging lug out of engagement with the crown teeth and stopping the machine the instant the revolution has been completed and the hat body is at the raised position, the parts being locked in this position as already stated by the engagement of roller 47 with one of the notches in cam 45 as clearly shown in Fig. 8.

Turning now to Figs. 9, 10, 11 and 12 in connection with Fig. 1, I will explain the operation of the dipping mechanism and of the mechanism for retarding the movement of the hat body when it is sinking in the tank and for retarding the movement when the body is being raised from the tank. By the term retarded I mean that the movement in

both directions commences at the maximum speed and gradually grows slower.

The dipping mechanism is clearly illustrated in detail in Figs. 11 and 12.

It will of course be understood that motion is transmitted from main shaft 11 to shaft 12 which I have termed the secondary shaft. So far as the dipping mechanism itself is concerned this motion might be transmitted in any suitable manner as by a pinion on each shaft meshing with a pinion of equal size on the other shaft. The mechanism which I employ and which produces a gradually retarded motion when the body is moving downward and also a gradually retarded movement when the body is moving upward will be described later on.

76 denotes a gear and 77 a slightly smaller gear both of which together with sprocket wheel 13 are keyed to a sleeve 78 which turns freely on the main shaft, said sleeve being held in position thereon by a screw 79 engaging the end of the shaft.

80 denotes a mutilated gear keyed to shaft 12 the toothed portion of which engages gear 76, and 81 a smaller mutilated gear also keyed to shaft 12 the toothed portion of which engages an idle gear 82 which is journaled on a 95 bracket 83 rigidly secured to the frame, idle gear 82 also engaging gear 77 on sleeve 78. It should be understood that gears 76 and 77 and the sprocket wheel move together and that gears 80 and 81 move together, the idle 100 gear engaging gear 77 and the mutilated gear 81.

The operation of this portion of my invention is as follows: So far as this mechanism is concerned shaft 12 is the driving shaft. Suppose now that a hat body is placed upon the carrier for dipping, the carrier being in the position shown in Fig. 1, and that the operator starts the dipping mechanism by a pull upon operating cord 40. The gearing of the 105 dipping mechanism will at this moment be in the position shown in Fig. 11. The instant motion is communicated to shaft 12 the toothed portion of mutilated gear 81 will begin to rotate in the direction of the arrow and 110 will engage idle gear 82 which in turn will engage gear 77 upon sleeve 78 and will cause the sprocket wheel to turn from back to front as the parts appear in Figs. 1 and 12. This will lower the hat body in the tank, the downward movement of course continuing until the toothed portion of mutilated gear 81 passes out of engagement with idle gear 82. At this instant the hat body upon the carrier will be wholly submerged in the tank and an instant 115 later the movement of the operative portion of the machine will be stopped in the manner already described, in which position the parts will remain until the main shaft is again started automatically, which will not be until 120 the body has remained submerged for the desired length of time. At the instant the movement of the main shaft again commences, for the purpose of raising the body from the tank,

the toothed portion of mutilated gear 80 will pass into engagement with gear 76. This position is not shown in the drawings, Fig. 11 showing a position in which the toothed portion of mutilated gear 80 is just passing out of engagement with gear 76. It is believed however, that this position will be clearly understood from Fig. 11 in connection with the description. The toothed portion of mutilated gear 81 will now be wholly out of engagement with idle gear 82, and gear 76. The sleeve and the sprocket wheel will now receive motion directly from shaft 12 through the engagement of the toothed portion of mutilated gear 80 with gear 76 and its motion will of course be in the reverse direction from that indicated by the arrows so that the sprocket wheel will wind up the chain and lift the carrier and the body thereon out of the tank. It will of course be understood that during this movement the idle gear will simply be carried by gear 77 but will perform no function whatever, the operative function of the idle gear being to receive motion from the toothed portion of mutilated gear 81 and to communicate motion to gear 77 in lowering hat bodies into the tank.

Turning now to Figs. 9 and 10 in connection with Fig. 1, I will explain the operation of the mechanism for retarding the movement of the sprocket wheel and carrier when the hat body is descending and for again retarding the movement when it is rising from the tank.

84, see Fig. 10, denotes a mutilated eccentrically mounted elliptical gear keyed to shaft 11 and 85 an eccentrically mounted elliptical gear keyed to shaft 12 which meshes therewith. These are the gears which communicate motion from the main shaft to shaft 12 to produce the downward movement of the hat bodies. The ellipticity of gears 84 and 85 and also of gears 87 and 88, presently to be described, is so slight as not to be observable in a figure of the size of those shown. It is moreover a necessity of construction and is merely a matter of mechanical skill in laying out the gears. No attempt therefore has been made to indicate ellipticity in the drawings. Both gears are provided with reinforces 86 for the purpose of strengthening the tooth which is engaged by the other gear at the beginning of each lowering operation.

It will be noticed that at the starting point the long radius of the driving gear registers with the short radius of the driven gear and that as the movement proceeds the operative radius of the driving gear will constantly grow shorter and the operative radius of the driven gear will constantly grow longer thus producing a constantly retarded movement of the driven shaft. This constantly retarded movement of shaft 12 will be communicated by means of the mechanism recently described to the sprocket wheel and will cause the carrier and the hat body thereon to be lowered in the tank with a constantly retarded move-

ment which will continue until the toothed portion of mutilated gear 84 passes out of engagement with gear 85. At the instant that these gears pass out of engagement the rotation of the main shaft will be stopped in the manner already described the hat body on the carrier being wholly submerged in the tank.

87, see Fig. 9, denotes another mutilated eccentrically mounted elliptical gear keyed to the main shaft and 88 another eccentrically mounted elliptical gear keyed to shaft 12 both of these gears being provided with reinforces 86 the same as gears 84 and 85. At the beginning of the downward movement of the carrier and hat body gears 87 and 88 will be in the position shown in Fig. 9, the toothed portion of mutilated gear 87 having passed out of engagement with the toothed portion of gear 88. At the instant that the movement of gears 84 and 85, just described, is completed gears 87 and 88 will be at the same position relatively to each other that gears 84 and 85 are in Fig. 10, that is to say, the engaging teeth of said gears will be just in position to engage the instant that the movement of the main shaft commences again, and gears 84 and 85 will be in the same position relatively to each other that gears 87 and 88 are in Fig. 9, that is to say, the toothed portion of mutilated gear 84 will have passed out of engagement with gear 85.

It will be understood from the above that during the first half revolution of the main shaft gears 87 and 88 are inoperative and gears 84 and 85 are operative in communicating motion from the main shaft to shaft 12. It follows therefore that during the second half revolution of the main shaft gears 84 and 85 will be inoperative and gears 87 and 88 will be operative. The instant that mutilated gear 87 begins to communicate motion to gear 88 the long radius of the driving gear will register with the short radius of the driven gear and as the movement proceeds the operative radius of the driving gear will constantly grow shorter and the operative radius of the driven gear will constantly grow longer so that the motion of shaft 12 will be constantly retarded which motion will be communicated through the mechanism just described to the sprocket wheel and will raise the hat body from the tank with a constantly retarded motion just as it is lowered by the reverse movement with a constantly retarded motion—that is to say, the movement of the hat bodies while being lowered into the tank and while being raised therefrom is made as fast as is practicable at the start but is constantly retarded to the end of the movement.

By imparting to the carrier a rapid movement when no harm can result therefrom I give to the machine the greatest possible capacity for work. By retarding the downward movement of the carrier I do away with all danger of forcing the air within the body through it so violently as to injure it to the slightest extent and by retarding the upward

movement of the carrier I avoid all danger of splashing or throwing water out of the tank.

The operation of the machine as a whole has been so fully described in the description of the several mechanisms as hardly to require further description. It is sufficient to say that after each raising movement the machine is automatically stopped by the engagement of latch 25 with lever 26 and the engagement of roller 47 with one of the notches on cam 45 exactly in position ready for starting again. All the operator is required to do to dip a hat body is to place a cone with a body thereon on the carrier and pull the operating cord, the entire operation of the machine being automatic. When the operator pulls upon cord 40 lever 26 is released so that spring 24 will force sliding block 21 forward and will place lug 20 in engagement with the crown teeth on the large gear wheel. This imparts movement to the main shaft and lowers the body on the carrier into the tank with a gradually retarded movement. At the instant the hat body has become fully submerged in the tank latch 25 will engage cam 42 on sliding collar 43 which will move lug 20 out of engagement with the crown teeth on the large gear wheel and will stop the operating mechanism, the hat body remaining submerged in the tank until collar 43 carrying cam 42 shall be automatically lifted permitting spring 24 to throw the latch forward again and place lug 20 in engagement with the crown teeth on the large gear wheel. Motion is thus automatically communicated to the main shaft again and the body is raised from the tank with a constantly retarded movement stopping instantly by the engagement of latch 25 with lever 26 when the carrier has reached the raised position.

Having thus described my invention, I claim—

1. In combination a carrier for hat bodies, a dipping wheel from which the carrier is suspended, mechanism for rotating the dipping wheel in opposite directions with a retarded movement so that in raising and lowering a hat body the movement grows slower from start to finish thereby preventing air from being forced through the body in the downward movement and preventing splashing of water in the upward movement and mechanism for retaining the carrier at the lowered position for any desired length of time.

2. In combination gears 76 and 77 and the dipping wheel moving together, idle gear 82 meshing with gear 77, and mutilated driving gears 80 and 81, the toothed portion of said mutilated gear 80 engaging gear 76 and the toothed portion of said mutilated gear 81 engaging idle gear 82 whereby when mutilated gear 81 and idle gear 82 are in engagement the latter communicates motion to gear 77 and the dipping wheel and when mutilated gear 80 engages gear 76 said gear and the dipping wheel are rotated in the opposite direction.

3. In combination shafts 11 and 12, suitable means for communicating motion from one shaft to the other, sleeve 78 journaled on shaft 11 and carrying gears 76 and 77 and the dipping wheel, gear 82 meshing with gear 77, and mutilated driving gears 80 and 81 carried by shaft 12, the toothed portion of said mutilated gear 80 engaging gear 76 and the toothed portion of said mutilated gear 81 engaging the idle gear, so that rotary movement of the shafts will cause alternate movement of the dipping wheel in opposite directions.

4. In combination a carrier for hat bodies, a dipping wheel from which the carrier is suspended, mechanism for rotating the dipping wheel in opposite directions with a retarded movement and mechanism substantially as described and shown for retaining the carrier at the lowered position for any desired length of time.

5. In combination shafts 11 and 12, the dipping wheel journaled on shaft 11, mechanism intermediate said shafts whereby the dipping wheel is moved alternately in opposite directions, eccentrically mounted gears 85 and 88 on shaft 12, and eccentrically mounted mutilated gears 84 and 87 on shaft 11, the toothed portions of said mutilated gears engaging the corresponding gears alternately whereby successive retarded movements are imparted to shaft 12.

6. The combination with shafts 11 and 12, the dipping wheel journaled on shaft 11 and mechanism intermediate said shafts for alternately imparting retarded movement in opposite directions to the dipping wheel, of eccentrically mounted gears 85 and 88 on shaft 12 and eccentrically mounted mutilated gears 84 and 87 on shaft 11 whereby successive retarded movements are imparted to shaft 12.

7. In a machine of the character described the combination with shaft 11, wheel 17 journaled thereon and provided with crown teeth 19, a plate 22 carried by said shaft and provided with a spring actuated sliding block 21, said block having a lug 20 adapted to engage the crown teeth and a latch 25, of block 28, spring actuated block 37 carried thereby and having a stump 35, operating rod 39 connected to block 37 and lever 26 against which the latch bears and which normally bears against stump 35 so that when block 37 and the stump are pulled down the lever will be released and the latch will move outward and place the engaging lug in engagement with the crown teeth whereby the motion of wheel 17 will be communicated to shaft 11.

8. In a machine of the character described the combination with shaft 11, wheel 17 journaled thereon and provided with crown teeth 19, plate 22 carried by said shaft, sliding block 21 having a lug 20 adapted to engage the crown teeth and a latch 25, and a spring 24 adapted to move the sliding block forward, of block 28, block 37 carried thereby and having a stump 35, operating rod 39 connected to block 37, spring 38 adapted to hold block 37

at the raised position and a lever 26 against which the latch bears and which normally bears against the stump said lever having a notch 33 which receives the stump when the latter is moved downward and permits spring 24 to move the sliding block outward and place the engaging lug in engagement with the crown teeth, spring 38 acting to return the stump and operating rod to their normal position as soon as the latch passes off from the lever.

9. In a machine of the character described the combination with shaft 11, wheel 17 journaled thereon and provided with crown teeth 19, plate 22 carried by said shaft and provided with a spring actuated sliding block 21, said block having a lug 20 adapted to engage the crown teeth and a latch 25, of suitable means for holding the sliding block backward against the power of the spring to keep the engaging lug out of engagement with the crown teeth and for releasing said block so that the lug will move into engagement with the crown teeth and a cam 42 which is engaged by the latch and moves the engaging lug backward out of engagement with the crown teeth thereby stopping the movement of the shaft.

10. In a machine of the character described the combination with shaft 11, wheel 17 journaled thereon and provided with crown teeth 19, plate 22 on said shaft carrying spring actuated sliding block 21 having engaging lug 20 and latch 25, suitable means for normally retaining the engaging lug out of engagement with the crown teeth, and suitable means for holding said block backward against the power of the spring so that the lug will not engage the crown teeth and for releasing said block so that the lug will engage the crown teeth, of sliding collar 43 carrying a cam 42 which when engaged by the latch moves the block backward and disengages lug 20 from the crown teeth stopping the rotation of the shaft, and suitable means for raising said collar and cam from engagement with the latch so that the block will again move forward and place lug 20 in engagement with the crown teeth and communicate motion to the shaft.

11. In a machine of the character described the combination with shaft 11, wheel 17 journaled thereon and provided with crown teeth 19, plate 45 secured to said shaft and provided with notches 46, plate 22 secured to said shaft and provided with a spring actuated sliding block 21, said block having a lug 20 adapted to engage the crown teeth and a latch 25, of suitable means for holding the sliding block backward against the power of the spring to keep the engaging lug out of engagement with the crown teeth and for releasing said block so that the lug will move into engagement with the crown teeth, a cam 42 which is engaged by the latch and moves the engaging lug backward out of engagement with the crown teeth thereby stopping

the movement of the shaft and a spring actuated roller 47 carried by an arm which engages either of the notches 46 and locks the shaft against further movement at the instant the engaging lug is moved out of engagement with the crown teeth.

12. In a machine of the character described the combination with shaft 11, wheel 17 journaled thereon and provided with crown teeth 19, and plate 22 carried by said shaft and provided with a spring actuated sliding block 21, said block having a lug 20 adapted to engage the crown teeth and a latch 25, of sliding collar 43 having a cam 42 which when engaged by the latch moves the sliding block backward and disengages the lug from the crown teeth, and vertically movable arm 74 which is adapted to engage the sliding collar and move the cam out of engagement with the latch so that lug 20 will move into engagement with the crown teeth again.

13. In a machine of the character described the combination with shaft 11, wheel 17 journaled thereon and provided with crown teeth 19, cam 66 on said shaft, plate 22 carried by said shaft and provided with a spring actuated sliding block 21, said block having a lug 20 adapted to engage the crown teeth and a latch 25, of sliding collar 43 having a cam 42 which when engaged by the latch moves the sliding block backward and disengages the lug from the crown teeth, vertically movable arm 74, vertically adjustable rod 69 by which said arm is carried a block 54 by which said rod is carried, screw shaft 57 and a lever 62 carrying a threaded block 63 which is adapted to engage the screw shaft when the lever is moved inward by cam 66 whereby arm 74 is moved upward and engages sliding collar 43 and moves the cam out of engagement with the latch so that lug 20 will move into engagement with the crown teeth again.

14. The combination with shaft 11, driving mechanism therefor the dipping wheel journaled on said shaft, the carrier, and mechanism whereby the dipping wheel is rotated in opposite directions to raise or lower the carrier, of mechanism for connecting shaft 11 and the driving mechanism and for disconnecting the driving mechanism when the carrier is at the lowered position and automatic mechanism substantially as described and shown whereby shaft 11 and the driving mechanism are again connected after the carrier has remained at the lowered position for a predetermined length of time.

15. In a machine of the character described the combination with the carrier and a dipping wheel from which it is suspended, of mechanism for rotating the dipping wheel in opposite directions with a retarded movement so that both in ascending and descending the movement of the carrier will grow slower from start to finish.

16. In a machine of the character described the combination with a vertically movable carrier, shaft 11, wheel 17 journaled on said

- shaft and suitable means for connecting said shaft and wheel at the beginning of the lowering movement and for disconnecting them at the end of the raising movement, of sliding 5 collar 43 carrying a cam 42 by which said shaft and wheel are disconnected at the end of the lowering movement, vertically movable block 54 and an adjustable arm 74 moving in connection with said block by which collar 43 and the cam may be moved out of operative position and said shaft and wheel again connected after the carrier has remained at the lowered position for a predetermined length of time.
- 15 17. In a machine of the character described the combination with a vertically movable carrier, shaft 11 carrying a cam 66, wheel 17 journaled thereon and suitable means for connecting said shaft and wheel at the beginning 20 of the lowering movement and for disconnecting them at the end of the raising movement, of collar 43 carrying a cam 42 by which said shaft and wheel are disconnected at the end of the lowering movement, screw shaft 57,

vertically movable block 54, lever 62 pivoted 25 to said block and carrying a threaded block adapted to engage the screw shaft, a spring acting to normally hold the threaded block out of engagement, arm 74 by which collar 43 and the cam may be moved out of operative position, a rod 69 which turns within arm 74 but moves said arm in the vertical plane, said rod being vertically adjustable 30 relatively to block 54 thus determining the time that must elapse after the threaded block has been moved into engagement with the screw shaft by cam 66 and shaft 11 and wheel 17 have been disconnected before arm 74 will engage collar 43, move the latter out of position and permit wheel 17 and shaft 11 35 to be again connected to produce the raising movement of the carrier.

In testimony whereof I affix my signature in presence of two witnesses.

CHARLES S. PECK.
